OPTICAL IMAGE-FORMING DEVICES

Stephen M. MacNeille, Thompson, Conn., assignor to
American Optical Company, Southbridge, Mass.

Filed Aug. 18, 1958, Ser. No. 755,769

3 Claims. (Cl. 313—92)

This invention relates to improvements in optical image-forming and transferring devices of the type embodying a multiplicity of elongated relatively slender light-conducting elements or fibers in group formation and has particular reference to improved means and method for forming optical images of increased brilliance at a first object plane and transporting said images to a second or image plane without appreciable loss of light or deterioration of the resolution or contrast of said images during transit.

In devices employing the use of cathode ray tubes, there has long been a need for tubes which are capable of producing optical images of increased brilliance without deterioration of image resolution or contrast.

It is well known that one can observe increased brightness from a phosphor layer excited by an electron beam by increasing the thickness of the phosphor layer and simultaneously increasing the voltage of the electron beam. The optimum situation is that in which the phosphor thickness and beam voltage are such that the electrons are just stopped by the phosphor. In this way, light is generated throughout the entire thickness of the phosphor during the slowing down of the electrons by said phosphor. During this slowing down stage, light produced per electron is at its maximum.

Since the size of the light spot increases rapidly with the thickness of the phosphor layer, the thickness of the layer must not be allowed to exceed an amount of the order of magnitude of the desired spot diameter. Therefore, in conventional cathode ray tubes, a limitation is imposed upon the increasing of the thickness of the phosphor layer and electron beam voltage by the degree of light scattering within the phosphor layer itself. That is, in order to produce images which are of acceptable resolution and contrast, it has been necessary heretofore in conventional cathode-ray tubes to restrict the thickness of the phosphor layer and, accordingly, the voltage of the electron beam so as to prevent an excessive lateral spreading of the light spots formed by the electrons striking the phosphor which spreading, when excessive, causes an overlapping of the light from adjacent light spots.

The present invention overcomes the problems previously encountered in increasing the brilliance of images formed by cathode ray tubes by providing novel means for permitting the thickness of phosphor and the voltage of the electron beam of such tubes to be increased as desired without detriment to image resolution or contrast.

It is, therefore, a primary object of this invention to provide an optical image-transporting device and method of making the same for transferring image-forming light from one location to another, said device having means for providing images of high quality resolution and brilliance.

Another object is to provide improved fiber optical face plates for cathode ray tubes.

2

Another object is to provide novel means on face plates of the above character for producing spots of image-forming light when bombarded electronically and for controllably restricting the lateral scattering of light from said spots.

Another object is to provide a face plate of the above character which is formed of an assembly of a great number of coated or clad light-conducting filaments or fibers bundled together in connected side-by-side relation with

10 each other with their opposite ends optically finished to be receptive to light and a cellular structure in optical contact with one side of said assembly of a precontrolled thickness, the individual cells of said structure each having light-reflective side walls and each being substantially 15 filled with phosphorescent material whereby light produced by said material, when electronically bombarded, will be prevented from spreading laterally beyond the limits of the cell walls and will be directed only into the fibers which are in end contact with the respective adjacent 20 cells.

Another object is to provide a face plate of the above character wherein the brilliance of the light produced by said phosphor may be controlled as desired in accordance with the thickness of the above-mentioned cellular structure and the lateral spreading of the light produced by the phosphorescent material within the individual cells thereof may also be controlled as desired in accordance with the individual cell size of said structure.

A further object is to provide a relatively simple, yet 30 highly efficient, image-producing and transferring face plate which when used in conjunction with cathode ray tubes or the like is adapted to improve the image-producing capabilities of such tubes by providing means for producing images of a high degree of resolution which 35 are considerably more brilliant than has heretofore been possible.

Other objects and advantages of the invention will become apparent from the following description when taken in conjunction with the accompanying drawings in which:

40 Fig. 1 is a partially cross-sectioned diagrammatic side elevational view of a cathode ray type of electronic tube embodying this invention;

Fig. 2 is a greatly enlarged fragmentary cross-sectional view of the image-forming face part of the cathode ray 45 tube illustrated in Fig. 1;

Fig. 3 is a fragmentary exploded view illustrating in greater detail the structure of the face part of said cathode ray tube;

Fig. 4 is a still further enlarged fragmentary cross-sectional view of the face part of Figs. 1, 2 and 3 wherein there is diagrammatically illustrated the light-gathering and transmitting characteristics of said face part; and

Fig. 5 is a greatly enlarged cross-sectional view of a modified form of the device of the invention.

55 Referring more particularly to the drawings, there is illustrated in Fig. 1 a cathode-ray type of electronic tube 10 having an image-forming face plate 11 embodying a forwardly directed light-conducting section 11a formed of a great number of individually light-insulated or clad 60 light-conducting fibers 12 arranged in connected side-by-side relation with each other and a rearward image-forming section 11b disposed within the vacuumized body of the tube 10 and in optical contact with the fibers 12 (see Figs. 2 and 3). The section 11b of the face plate 11 is in the form of a cellular structure 13, the individual 65 cells of which are filled with a phosphorescent material 14 of the well known type commonly used to produce image-forming light in conventional cathode ray tubes. When bombarded by electrons, the phosphorescent ma-

terial will become luminous and being in optical contact with fibers 12, the light produced by the material 14 will pass into the fibers 12 and be transferred thereby to the outer surface of the face plate 11.

It is pointed out that other than the face plate 11, the cathode ray tube 10 is strictly conventional in nature and may be of any shape, size or design to fulfill the requirements of the particular apparatus with which it is to be used and the face plate 11 of this invention is formed to an outer contour shape and size in accordance with that required for the particular tube to which it is to be applied.

The fibers 12 are initially formed individually with core parts of light-conducting material having a relatively high index of refraction such as, for example, a flint glass and outer coatings or claddings of material having a relatively low index of refraction such as, for example, a crown glass. The fabrication of the fibers 12 may be accomplished by placing a rodlike member of the high index material within a relatively thin walled tubular member of the low index material and heating the assembly to a fiber-drawing viscosity whereupon it is drawn to a desired size. It is particularly pointed out that the fibers 12 may be formed by any of the known techniques or of any of the known materials common to the manufacture of conventional light-insulated or clad fibers.

In forming the section 11a of the face plate 11, the fibers 12 are placed in side by side parallel relation with each other and fused or otherwise securely bonded together to form an assembly having an airtight seal between each of the fibers. Reference may be made to an application for patent bearing Serial Number 715,406, filed February 14, 1958, in the name of Wilfred P. Bazinet, Jr., for more detailed information regarding one method by which such assemblies of fibers may be made.

Having made an assembly of fibers 12, the assembly is cut or otherwise formed to a desired thickness and the opposite sides thereof are optically ground and polished to render the ends of the fibers 12 readily receptive to light.

It should be understood that although the fibers 12 have been illustrated as being generally square in cross-sectional shape, they may alternatively be hexagonal, octagonal or of any other desired cross-sectional shape, it being only important that upon being fused or otherwise bonded together, they be in intimate connected relation with each other to form a completely airtight structure which when assembled with the enlarged envelope of the cathode ray tube 10, as shown in Figs. 1 and 2, the assembly will form an airtight seal for the end of said envelope thereby permitting the usual necessary vacuum to be provided within the interior of the tube 10.

Various methods suggest themselves for the fabrication of the cellular structure 13 which forms the inner portion of the face plate 11, one of which would be to assemble a bundle of thin-walled glass tubes in a manner similar to the assembling of the fibers 12 discussed above. Upon assembly, the tubes are fused or otherwise securely bonded together and the assembly cut transversely to a desired thickness in accordance with the thickness desired of the phosphorescent material 14 which will be discussed in greater detail hereinafter. If it is required that the tubes be of extremely small cross-sectional size, wherein some difficulty might be encountered in precisely aligning the same during assembly, thin-walled tubes of a relatively large cross-sectional size may be assembled in side-by-side relation with each other and the assembly thereafter drawn and fused simultaneously to reduce the cross-sectional size of the tubes as desired. Structures such as 13 would then be cut from the drawn assembly to the thickness desired thereof.

In either of the above-mentioned cases, the resultant thin-walled tubular or cellular assembly is provided with opaque and reflective side walls by gas plating, evaporation, chemical silvering, or the like.

Another method of fabricating the cellular structure 13 consists of forming the structure of metal tubes which are welded or soldered together. A cellular structure 13 of thin-walled metal tubes may be fabricated by cladding wires formed of copper or other similarly characterized metals with a plating metal such as gold or the like which is highly resistant to attack by etching materials such as nitric acid or other suitable acid. The clad wires may be formed by the well known method of forming gold-filled wire wherein a rod of copper is placed within a tube of gold and the assembly is rolled to a desired wire size.

An assembly is then made of a great number of the plated or clad wires by placing them in side-by-side parallel relation with each other whereupon the wires are secured together. The assembly is then cut transversely into sections of the thickness desired of the cellular structure 13 and the wires are etched out of the sections to leave a cellular structure 13 consisting of only the claddings. The wires, if made of copper, may be etched out of the structure 13 by placing the same in a solution consisting of equal parts of nitric acid and water. Other combinations of metals and etching solutions may be readily substituted for the examples given above, and it should be understood that said examples have been given by way of illustration only.

If it is required that the cell size of the structure 13 be extremely small, the secured assembly of plated or clad wires may be rolled to a reduced size prior to the etching out of the wires. In this manner, when the assembly is finally cut and etched, the cross-sectional size of the remaining cellular-like claddings will be of reduced cross-sectional size in accordance with the extent to which the assembly is reduced in size by the rolling or other similar operation.

The cellular structure 13 is so formed that it may be placed in direct contact with the side of the light-conducting section 11a which is to be disposed inwardly of the tube 10. If formed of glass tubing, the structure 13 is fused or cemented to the light-conducting section 11a and if formed of metal, it is cemented in place with a glass-to-metal bond of any well known type, a great variety of which are readily available commercially.

The cells of the structure 13 are filled, preferably level full, of the phosphorescent material 14 either before or after the structure 13 is assembled with the light-conducting section 11a. The filling of the cells of the structure 13 is accomplished by forming a liquid or paste-like mixture of phosphor powder and water glass in the conventional manner well known and commonly practiced in cathode ray tube manufacture whereupon the mixture is forced into the cells of the structure 13. In filling said cells, care must be taken to avoid the trapping of air in the cells. By filling the structure 13 before it is attached to the section 11a of the face plate, there will be little danger of trapping air within the cells since the cells of the structure 13 are open at each end. It should be understood that vapor deposition techniques or other known methods of filling the cells with phosphor may be used if desired.

When assembling the cellular structure 13 with the light-conducting section 11a of the face plate 11, no attempt is made to register each of the cells of the structure 13 with a corresponding fiber since in constructing both the light-conducting section 11a and the cellular structure 13, the cross-sectional size of the respective fibers and cells thereof are formed of a size small enough to each, in themselves, have a high enough resolution so that any loss of resolution due to lack of registration would be negligible and the overall image-resolving power of the face plate 11 will be such as to produce clear and distinct images. However, in order to improve the image resolution, it has been found to be of advantage to construct the section 11a and structure 13 with fibers and cells respectively which differ in cross-

sectional sizes. For example, the cross-sectional size of the fibers 12 may be somewhat smaller than the cross-sectional size of the cells in the structure 13, as illustrated, or, alternatively, the cells may be smaller than the fibers, it being immaterial as to which choice is made. In this manner, a continuity in the relative positions of the cladding parts of the fibers and the sidewall parts of the cells is avoided when the section 11a and structure 13 are in assembled relation with each other and no distinct line pattern is produced by said claddings and side wall parts. It is pointed out that the cross-sectional shapes of the fibers and cells need not be similar, as shown in the drawings, that is, square fibers may be used with circular, hexagonal, octagonal or other differently shaped cells or square cells may be used with hexagonal, octagonal or other differently shaped fibers.

It should be understood that it is well within the scope of this invention to form structures such as 13 and light-conducting sections such as 11a with cells and fibers respectively which are of identical sizes and shapes and to assemble the parts of the face plate 11 in such a manner as to cause each of said cells to be in registry with a respective adjacent fiber. However, such a construction would not materially improve the resolution of images produced and transmitted by the face plate over the above-mentioned construction and would cause the fabrication of the face plate to become somewhat more complicated and expensive.

In order to more clearly understand the reasons for constructing the face plate 11 as described above, reference is now made to Fig. 4 wherein a greatly enlarged cross-sectional view of the face plate 11 is illustrated.

Image light is formed in cathode ray tubes by bombarding a phosphorescent material with electrons emitted as a beam with a velocity controlled in accordance with the voltage applied to the electron gun or electron-emitting portion of the tube. Therefore, the voltage must be controlled in accordance with the thickness of the phosphorescent material or vice-versa so as to cause the electrons to be just stopped by the phosphorescent material for the reasons discussed hereinabove. Heretofore, a limitation has been placed upon the thickness to which the phosphor may be made, as was also discussed hereinabove, with the result that the brightness of the image-forming light cannot be increased beyond certain limits without detriment to the image resolution.

With the face plate 11 of this invention, light which is produced at a point 15, for example, or at any other point within one of the cells of the structure 13, will inherently be scattered in all directions surrounding said point and the laterally scattered light such as illustrated by the arrows 16 and 16', for example, will be reflected by the side walls of the respective cell and directed thereby only into the fibers 12 which are in end contact with said cell. Assuming that the phosphorescent material 14 were not deposited in a cellular structure such as 13 but was in the form of a conventional continuous layer, it can be seen that the light 16 or 16' would follow generally the path indicated by the respective dashed arrows 16a or 16b and be directed into other fibers 12 not disposed forwardly of the point 15 whereas some of the forwardly directed light from the point 15 would simultaneously be directed into said forwardly disposed fibers. This effect would take place throughout the phosphorescent layer and cause an overlapping of light from various point sources to intermix the image-forming elements of the overall picture image being produced and thus cause a dilution or washing out of said elements with the result of poor image resolution.

Rather than reduce the thickness of the phosphorescent material so as to reduce the lateral scattering as has been the practice heretofore, the present invention provides the cellular structure 13 to confine the lateral spreading of the light to an area determined by the size of the cells whereby the light-reflecting side walls of said cells will

cause said light to emerge only into the fibers 12 immediately adjacent thereto.

Upon receiving light from the cells of the structure 13, the fibers 12, being individually light-insulated, function to conduct said light to the viewing face 17 of the face plate 11 and in so doing, prevent a further scattering of the light from the structure 13 thereby overcoming the effects of parallax, or halation common to conventional face plates which are formed of solid glass plates.

From the above, it can be seen that the brightness of the image-forming light can be increased as desired by increasing the thickness of the cellular structure 13 and increasing the voltage of the electron beam accordingly, the optimum situation being that in which the thickness of the phosphorescent material 14 and the electron beam voltage are such that the electrons are just stopped by the material 17 upon reaching the interfacial surface between the material 14 and the fibers 12. Furthermore, it should be apparent that for a given thickness of phosphorescent material 14 and voltage of the electron beam, the resolution of the picture image formed by the face plate 11 is improved as the cell sizes and fiber sizes are reduced to within practical limits. The cell and fiber sizes should not be so small as to approach the wavelength of light.

A face plate 11 which is approximately two inches in diameter and of an overall center thickness of approximately one-fourth of an inch with fibers 12 which are .002 inch in diameter and embodying a cellular structure 13 of approximately .010 inch thick with cells of approximately .003 inch in diameter will produce high quality images in accordance with this invention. It should be clearly understood that the above dimensions have been given by way of example only and should not, in any way, limit this invention since the fiber and cell sizes and other dimensions of the face plates are selected to fulfill the particular requirements of the apparatus in which the cathode ray tube 10 is used.

In Fig. 5, there is shown a modified face plate 18 which is similar in character to the face plate 11 just described. The face plate 18 is fused or otherwise secured to the forward end of a cathode ray tube 10 to form the image-forming face of the tube 10. The face plate 18 embodies a multiplicity of clad light-conducting fibers 19 which are fused, cemented or otherwise connected in side-by-side intimately grouped relation with each other so as to form an airtight seal for the forward end of the tube 10. The face 20 of the assembly of fibers 19 is optically finished and the core parts 21 of each of the fibers 19 are recessed at the opposite side of the assembly to a depth in accordance with the thickness desired of the phosphorescent material 23 which fills said recesses. The inner side surfaces 24 of the portion of the claddings 22 which form the side walls of the recesses are rendered opaque and reflective and light formed in said recesses by the phosphorescent material 23 therein is restricted from lateral spreading beyond the confines of the surfaces 24 and directed into the core parts 21 of the fibers 19 in the manner disclosed with regard to the face plate 11. In short, the face plate 18 is equivalent to the face plate 11 in that the phosphorescent material 23 is deposited in a cellular structure within the interior of the tube 10, which cellular structure, in this case, embodies the recessed core parts 21 of the fibers 19.

In fabricating the face plate 18, the fibers 19 are initially formed with core parts 21 of a relatively high index glass or similar material such as, for example, a flint glass which may be readily etched with a solution of one part 5% hydrofluoric acid and one part 5% hydrochloric acid or other suitable solutions. The cladding parts 22 of the fibers 19 are formed of a relatively low-index glass or similar material such as for example, an aluminum metaphosphate glass or the like which is substantially impervious to attack by the above-mentioned

etching solution. Following the forming of the fibers 19, they are assembled in fused or otherwise connected side-by-side relation with each other in the manner disclosed above for the fabrication of the light-conducting section 11a of the face plate 11. The side of the assembly of fibers 19 which is to be disposed inwardly of the tube 10 is then placed in the etching solution for a period of time necessary to etch the core parts 21 and thus form the above-mentioned recessed areas between the claddings 22, the depth of said recessed areas being controlled in accordance with the thickness desired of the phosphor 22. Having provided the face plate 18 with the recessed areas, the side walls of said areas are rendered reflective at 24 as by gas plating, chemical silvering or other known methods of making mirrored surfaces and the recesses are thereafter filled with the phosphorescent material 23.

It is pointed out that in place of the reflective surface 24, the fibers 19 may be initially constructed with double claddings wherein a first cladding of transparent low-index glass or similar material would be surrounded with an opaque coating of metal or other suitable material which would not be attacked by the solution employed for the etching. In such a case, the first cladding would act to reflect the light through the core parts of the fibers 19 in the usual manner and the opaque outer coating would act to prevent lateral light-scattering which takes place in the phosphor 23 from passing through the side walls of the recesses in the face plate.

It is pointed out that various combinations of high and low index glass or similar light-conducting material may be used to fabricate the face plates of this invention as will be appreciated by anyone skilled in the art and this invention is not in any way limited to the examples of materials given hereinabove as all matters shown and described have been given by way of illustration.

From the foregoing, it will be seen that simple, efficient and economical means and method have been provided for accomplishing all the objects and advantages of the invention. Nevertheless, it should be apparent that many changes in the details of construction, arrangement of parts or steps in the process may be made without departing from the spirit of the invention as expressed in the accompanying claims.

Having described my invention, I claim:

1. A face plate for use with a cathode ray tube or the like embodying an electron gun and a fluorescent screen adapted to receive electrons emitted by said gun, said face plate comprising a plurality of very fine filamentlike light-conducting fibers bundled and secured together in adjacent side-by-side airtight relation with each other by a transparent material having a lower index of refraction than said fibers, said fibers being of pre-controlled length in accordance with the thickness desired of said face plate and having their respective adjacent end surfaces aligned to form a continuous surface part on at least one side of said face plate, a structure embodying a plurality of open-ended cells of relatively small diameter having relatively thin opaque walls secured in close side-by-side relation with each other to the opposite side of said face plate and being of a length substantially equal to the thickness desired of a phosphorescent material to be supported on said opposite side of said face plate, said cells opening outwardly away from and being in substantially parallel relation with said fibers, and phosphorescent material in each of said cells, said cells being of a length controlled in accordance with the increased thickness desired of said phosphorescent material over that which has been practical for use in conventional tubes of the type embodying a continuous layer of such material and being such as to enable the voltage of the electron gun to be accordingly increased over the voltages which were practical for use in such conventional tubes whereby a brighter image having increased resolution and definition may be obtained as the result of the

substantial elimination of scattering of the light by said thin opaque walls of said cells and the elimination of parallax and halation as results from said very fine light-conducting fibers.

2. A face plate for use with a cathode ray tube or the like embodying an electron gun and a fluorescent screen adapted to receive electrons emitted by said gun, said face plate comprising a plurality of very fine filamentlike light-conducting fibers each embodying a core of a transparent material of a relatively high index of refraction having a thin cladding of a transparent material of a relatively low index of refraction thereon and having highly reflective interfaces, said fibers being bundled and secured together in adjacent side-by-side airtight relation with each other, said fibers being of pre-controlled length in accordance with the thickness desired of said face plate and having their respective adjacent end surfaces aligned to form a continuous surface part on at least one side of said face plate, a structure embodying a plurality of open-ended cells of relatively small diameter having relatively thin opaque walls secured in close side-by-side relation with each other to the opposite side of said face plate and being of a length substantially equal to the thickness desired of a phosphorescent material to be supported on said opposite side of said face plate, said cells opening outwardly away from and being in substantially parallel relation with said fibers, and phosphorescent material in each of said cells, said cells being of a length controlled in accordance with the increased thickness desired of said phosphorescent material over that which was practical for use in conventional tubes of the type embodying a continuous layer of such material and being such as to enable the voltage of the electron gun to be accordingly increased over the voltages which were practical for use in such conventional tubes whereby a brighter image having increased resolution and definition may be obtained as the result of the substantial elimination of scattering of the light by said thin opaque walls.
3. A face plate for use with a cathode ray tube or the like embodying an electron gun and a fluorescent screen adapted to receive electrons emitted by said gun, said face plate comprising a plurality of very fine filamentlike light-conducting fibers each embodying a core of transparent glass of a relatively high index of refraction having a thin cladding of transparent glass of a relatively low index of refraction thereon and having highly reflective interfaces, said fibers being bundled and secured together in adjacent side-by-side airtight relation with each other, said fibers being of pre-controlled length in accordance with the thickness desired of said face plate and having their respective adjacent end surfaces aligned to form a continuous surface part on at least one side of said face plate, a structure embodying a plurality of open-ended cells of relatively small diameter having relatively thin opaque walls secured in close side-by-side relation with each other to the opposite side of said face plate and being of a length substantially equal to the thickness desired of a phosphorescent material to be supported on said opposite side of said face plate, said cells opening outwardly away from and being in substantially parallel relation with said fibers, and phosphorescent material in each of said cells, said cells being of a length controlled in accordance with the increased thickness desired of said phosphorescent material over that which has been practical for use in conventional tubes of the type embodying a continuous layer of such material and being such as to enable the voltage of the electron gun to be accordingly increased over the voltages which were practical for use in such conventional tubes whereby a brighter image having increased resolution and definition may be obtained as the result of the substantial elimination of scattering of the light by said thin opaque walls.

of said cells and the elimination of parallax and halation as results from said very fine light-conducting fibers.
